UNITED STATES PATENT OFFICE

146,242

DESIGN FOR AN AUTOMOTIVE CRANE BODY

Joseph W. Wunsch, Brooklyn, N. Y.

Application June 12, 1945, Serial No. 120,030

Term of patent 14 years

(Cl. D14—3)

To all whom it may concern:

Be it known that I, Joseph W. Wunsch, a citizen of the United States of America, residing at Brooklyn, county of Kings, city and State of New York, have invented a new, original, and ornamental Design for an Automotive Crane Body, of which the following is a specification, reference being had to the accompanying drawings, forming part thereof.

Fig. 1 is a side elevational view of an automotive crane body embodying my design.

Fig. 2 is a plan view of the automotive part of the crane body, the boom being omitted.

Fig. 3 is a front elevational view of the automotive part of the crane body, the boom being omitted.

Figure 4 is a rear perspective view illustrating the design.

The dotted line showing in the drawing figures is for illustrative purposes only.

I claim:

The ornamental design for an automotive crane body, substantially as shown and described.

JOSEPH W. WUNSCH.
